UNITED STATES PATENT OFFICE

EARL WILLIAM GRIFFITH, OF DALHART, TEXAS

ROTARY VALVE

Application filed June 9, 1930. Serial No. 460,000.

The present invention contemplates the provision of a new and improved rotary valve for internal combustion engines, and wherein a single rotating sleeve is continuously rotated during the operation of the engine, and from the shaft thereof.

In carrying out the invention, the head of the engine is provided with spaced inner and outer tubular casings, between which 10 rotates the valve sleeve, the latter having a plurality of openings arranged in staggered relation, and adapted to register with inlet and outlet ports of the casing at predetermined intervals, to properly control the inlet and exhaust to the cylinders of the engine.

In accordance with the present invention, the inner casing is divided by a longitudinal partition into inlet and exhaust passages 20 which are coextensive in length with the casing and closed at one and opposite ends, with said passages communicating with the adjacent inlet and exhaust ports of the head, and controlled by the rotary sleeve.

An important object of the invention resides in the provision of a valve of the above mentioned character, wherein the rotatable sleeve can be easily and quickly inserted between and removed from the spaced inner 30 and outer casings of the head without disturbing the latter, and designed to provide unobstructed communication with the intake manifold of the engine when in position for use.

The nature and advantages of the invention will be better understood when the following detail description is read in connection with the accompanying drawings, the 40 invention residing in the construction, combination and arrangement of parts as claimed.

In the drawings forming part of this application like numerals of reference indicate 45 similar parts in the several views and wherein:

Figure 1 is a fragmentary side elevation of an engine, partly in section showing the valve forming the subject matter of the invention.

Figure 2 is a longitudinal sectional view through the valve.

Figure 3 is a sectional view on line 3-3 of Figure 1.

Figure 4 is a view in elevation of the 55 rotary valve sleeve.

Figure 5 is a sectional view on line 5-5 of Figure 1.

Figure 6 is a sectional view showing the 60 position of the rotary valve sleeve on the compression stroke of the engine.

Figure 7 is a similar view showing the position of the rotary sleeve on the firing stroke.

Figure 8 is a similar view showing the 65 position of the sleeve on the exhaust stroke.

Referring to the drawings in detail 10 indicates an explosive engine of well known construction wherein the cylinders are indicated at 11 and each equipped with a piston 12. The head of the engine is provided with spaced inner and outer tubular casings 13 and 14 respectively, and each casing is provided with spaced parallel rows of inlet and exhaust ports for the cylinders of the engine. The inlet ports of the respective casings are aligned and indicated at 15, while the exhaust ports of the respective casings are aligned and indicated at 16. It is of course manifest that the number of ports can be varied depending upon the number of cylinders included in the engine construction.

As clearly illustrated in Figure 2 the inner casing 13 is divided by a longitudinally disposed partition 17 into an inlet chamber 18 and an exhaust chamber 19, and these chambers are arranged coextensive in length with said casings. The partition is formed with an end wall 20 which closes one end of the exhaust chamber 19, while the opposite end of the inlet chamber is in open communication with the intake manifold 21 of the engine. While one end of the intake manifold 21 communicates with the adjacent end of the inlet chamber 18, the opposite end of the manifold communicates with a passage 22 which passes through the stationary inner and outer casings 13 and 14 respectively.

A valve sleeve 23 is located between the inner and outer casings 13 and 14 respectively, and is continuously rotated during the operation of the engine. The valve sleeve 23 is closed at one end as at 24, and projecting from this end is a short shaft 25 which carries a small gear 26. While the valve sleeve may be rotated in any suitable manner, the gear 26 preferably meshes with a gear 27 carried by the engine shaft, so that the valve is continuously rotated during the operation of the engine. The valve sleeve 23 is provided adjacent one end with a circumferential series of spaced openings 28 which communicate with the adjacent end of the intake manifold 21 through the passage 22 above referred to. Consequently the charge of fuel can be readily admitted to the inlet chamber 18 while the valve sleeve is rotated. The shaft 25 carried by one end of the valve sleeve is journaled in a suitable cap or bearing 29 which closes the adjacent ends of the spaced inner and outer casings 13 and 14 respectively, and this cap 29 is bolted or otherwise suitably secured as at 30 to the engine head. By reason of this construction, it is obvious that the cap can be easily removed to permit the valve sleeve 23 to be either inserted within the space between the inner and outer casings 13 and 14 respectively, or removed therefrom as the occasion may require without disturbing the head of the engine.

The valve sleeve 23 is provided with a plurality of spaced openings 31 which are arranged in staggered relation throughout the length of the sleeve, and which openings are arranged to be brought into registration with the aligned inlet and exhaust ports of the spaced casings at predetermined intervals, and thereby properly control the inlet and exhaust to the cylinders of the engine.

In practice, the charge of fuel from the intake manifold 21 enters the inlet chamber 18 from the opposite ends thereof, and as clearly illustrated in Figure 3, when the piston 12 of a cylinder is about to start downwardly on its intake stroke, an opening 31 of the rotary valve sleeve is in communication with the inlet openings of the inner and outer casings for the particular cylinder. Consequently the fuel passes through these openings from the inlet chamber 18 to the cylinder. As illustrated in Figure 6, as the piston starts upwardly within the cylinder on its compression stroke, the valve sleeve 23 which continuously rotates during the operation of the engine has been moved to cover both the inlet and exhaust ports of the spaced inner and outer casings, and the position of the opening 31 of the sleeve occupies the position shown in Figure 6.

When the piston starts downwardly on its firing stroke, the inlet and exhaust ports of

the inner and outer casings are still closed by the valve sleeve, and the opening 31 thereof has moved to the position illustrated in Figure 7 incident to the continuous rotation of the sleeve. After the cylinder has been fired and the piston starts up on its exhaust stroke as illustrated in Figure 8, the valve sleeve has been shifted to the position illustrated in this figure, wherein it will be noted that the opening 31 has been brought into registry with the exhaust ports 16, so that the exhaust gases are admitted to the exhaust chamber 19 of the inner casing, from where they pass through an exhaust manifold not shown. When the valve sleeve 23 is in a position to establish communication between a particular cylinder and the exhaust chamber 19, the inlet ports for the particular cylinder are closed by the valve sleeve as illustrated in Figure 8.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

A rotary valve for explosive engines comprising spaced inner and outer stationary casings carried by the head of the engine, a longitudinal partition dividing the inner casing into inlet and exhaust chambers extending throughout the length of the casing, an end wall carried by the partition for closing the adjacent end of the exhaust chamber, said casings having aligned inlet and exhaust ports communicating with their respective chambers, a rotary valve sleeve insertable through an opening in one end of the head into the space between said inner and outer casings, a removable cap carried by said end of the head and closing the adjacent ends of said casings, said valve sleeve being closed at one end and having a circumferential series of spaced openings adjacent said end, said inlet chamber communicating at both ends with the inlet manifold of the engine, and through the spaced openings of the sleeve at one end thereof, and a shaft projecting from the closed end of the sleeve and journaled in said cap, whereby said sleeve can be rotated.

In testimony whereof I affix my signature.

EARL WILLIAM GRIFFITH.
